UNITED STATES PATENT OFFICE.

JAMES B. RICHARDSON AND SILAS J. ALLEN, OF PROVIDENCE, RHODE ISLAND; SAID ALLEN ASSIGNOR TO SAID RICHARDSON.

BUTTON.

SPECIFICATION forming part of Letters Patent No. 308,630, dated December 2, 1884.

Application filed February 18, 1884. (No model.)

To all whom it may concern:

Be it known that we, JAMES B. RICHARDSON and SILAS J. ALLEN, both citizens of the United States, residing in the city and county 5 of Providence, in the State of Rhode Island, have invented certain new and useful Improvements in Sleeve and Collar Buttons and Studs, of which the following is a specification.

Our invention relates to that class of buttons and studs in which there is a curved oscillating post actuated by a spring to automatically interlock with an oppositely curved stationary post; and it consists in the construction and assemblage of the several parts 15 of the button.

It has heretofore been customary to construct the back-plate of the button in two parts and solder the part containing the operative parts to the main portion of the back-plate; and the oscillating post and its actuating-spring have been heretofore jointed and revolved upon the same mandrel or pin.

In our invention we construct the back-plate in one piece and dispense with the mandrel or pin joint.

The objects of our invention are to strengthen the back-plate, to avoid breakage under the strain of the operative parts of the button, and to facilitate and cheapen the cost of manufacture, all of which we attain by the construction and arrangement shown, and hereinafter described.

Referring to the accompanying drawings, Figure 1 is a plan of the back-plate. Fig. 2 is a section of the same in elevation on line y y. Fig. 3 is a side view of the stationary post. Fig. 4 is a perspective view of the stationary post. Fig. 5 is a perspective view of the oscillating post. Fig. 6 is an elevation of the same. Fig. 7 is a plan of the retaining-disk. Fig. 8 is a plan of one form of the actuating-spring. Fig. 9 is an elevation in cross-section, showing the several parts assembled, the dotted lines indicating the movement and position of the oscillating post in unlocking the button for removal from the garment; and Fig. 10 is a section of the plate shown in Fig. 7.

Similar letters indicate similar parts, where they occur in the drawings.

A represents the back-plate, which may be of any desired outline, and it is provided with

a recessed chamber, A², depressed more deeply on one side than on the other. This chamber A² has still deeper recesses, A³, located at each end of a central orifice, A'. The back-plate, 55 A, is struck up from a single piece of stock, the chamber A², recesses A³, and slot A' all being formed at the same time. In striking it out we leave the corner pieces, d d, on one side of the orifice or slot A' and enlarge the 60 orifice on the opposite side, as at n.

E is a post, which is struck or cut from a single piece of stock, and having the part E' and open side slots, o o. The part E' is bent at right angles to the body of the post adjacent 65 to the slots o o, and the foot of the post is bent in the opposite direction, as shown in Figs. 3 and 4. When the part E is inserted through the orifice A', the part E' fits into the deeper part of the recess A², and the open side slots, 70 o o, receive and engage the corners d d of the back plate, imparting more rigidity to the post, which also may be riveted, soldered, or otherwise secured to the back-plate.

It will be observed that after the insertion 75 of this part E' in the deeper side of the chamber A² there will then remain a chamber of uniform depth divided centrally by the orifice A' and recesses A³ A³.

D is a curved post open-slotted at m, slotted 80 at k, and notched at x. It is cut from a single piece of stock to leave the journals or trunnions a a, and is then bent into the form shown in Fig. 6. These journals or trunnions a a fit into the recesses A³ A³ in the back plate when 85 the post D is inserted in the orifice A'. The spring s is coiled with two oppositely-extended ends, as shown in Fig. 8.

We do not confine our invention to the specific form of spring here shown. Any coil or 90 spiral spring can be used to equal advantage, as can also a flat or strap spring, except that, in case the flat spring were used, we would recommend omitting the open slot m in the post, so that the spring would bear across the entire end of the same.

B is a disk, which is struck from a single piece of stock and provided with the raised lugs c c and the recessed chamber b b'. This disk B retains the operative parts of the button in place. The raised lugs c c and recessed chamber b b', being struck up from the body 100

of the disk, act, respectively, to retain the post D in the sockets A³ A³ and to form a chamber for the spring s, which is arranged to lie partly in the chamber b and partly in the open slot 5 m of the post D, with one arm engaging the notch x in the post and the other arm lying between the back plate, A², and the disk B in the recess b'. The post D is thus hinged on the inner faces of the recesses A³ A³, and no securing-pin is required for it or the actuating-spring.

In practical manufacture of our invention, the several parts being constructed substantially as shown and described, the post D is 15 passed through the orifice A' until its trunnions a a fall into the recesses A³ A³. The post E is then passed through the orifice A' and slot k in the post D until the disk E fits into the deeper portion of the chamber A², and 20 the side slots, o o, engage the corners d d, and the disk is then riveted, soldered, or otherwise immovably secured to the back plate, affording a rigid fixed post. Then, if the actuating-spring is of the form shown in the drawings, it 25 is made to enter that part of the orifice A' unoccupied by the posts at n, so that one of its arms will extend outwardly through the orifice A' and engage the notch x in the post D, while the other arm will be retained in position along 30 the bottom of the chamber A² by the disk B, secured to the back plate, so that the spring will lie in the notch m of the post D partly, and partly in the recess b of the disk B, and the raised lugs c c will form bearing-surfaces, 35 against which the trunnions a a will work when the post D is oscillated to lock and unlock the button. The back plate then can be inserted in the rim of the button in the ordinary manner.

40 Modifications as to the form and proportions can be readily made by any good mechanic without departing from the principle or detracting from the utility of our invention.

We claim as our invention—

1. The combination of the back-plate A, provided with the unequally-recessed chamber A² and projected corners d d and depressed recesses A³ A³, with a post, E E', oppositely-curved post D, slotted at k and m and notched at x, and provided with trunnions a a, a spring, 50 s, adapted to actuate the post D automatically, to lock the button, as shown, and a retaining-disk, B, provided with raised lugs c c and chamber b b', all arranged and operating substantially as shown and described. 55

2. In a button and stud, a back-plate, A, provided with an unequally-recessed chamber, A², orifice A', with its interjected corners d d, depressed recesses A³ A³, all struck and cut from a single piece of stock, as shown, in combination with a retaining-disk, B, struck from a single piece of stock, with the recessed chamber b b' and the projecting recessed lugs c c, as shown. 60

3. In a button and stud, the combination of 65 a post, E, having a part, E', and the adjacent open side slots, o o, all struck from a single piece of stock, as shown and described, the said part E' and the foot of the post being turned at right angles to the body of the post 70 and oppositely to each other, with a post, D, provided with open slot m and notch x at the end, and slot k and trunnions a a, forming an integral part of the post, and all struck from a single piece of stock, as shown and described. 75

In testimony whereof we have hereunto set our hands this 16th day of February, A.D. 1884.

JAMES B. RICHARDSON.
SILAS J. ALLEN.
